1 Claim

ABSTRACT OF THE DISCLOSURE

A peripherally extending vertical wall having a passage therethrough communicating with a circular opening simulating a putting cup. The top surface of the wall has a first aperture for removably supporting a golf ball and a second aperture for removably supporting the head of a golf club having an extensible shaft. An article such as a clock or an ash tray may be supported in the opening simulating a putting cup.

This invention relates to a combination stand for an article of utility and a game device; for example, a stand for an ash tray, ash receiver, clock or other type of article adapted to be placed on a desk or table stand together with a golf club and a gold ball arranged in such a way to provide an ornamental article which could also be used as a practice golf putting device.

I also provide a removable collapsible golf club as a part of the invention which may be collapsed when the device is used as an ornamental device, and may be extended for use as a golf club when the invention is used as a game device.

I also provide for the stand portion which holds the article of utility to be used as a golf cup when the article of utility is removed.

The invention is illustrated in the accompanying drawings in which:

FIG. 1 is a perspective view with the shaft of the golf club in collapsed position, and an ash receiver shown mounted on the stand in dotted lines;

FIG. 2 is a rear elevational view of the device as shown in FIG. 1;

FIG. 3 is an elevational view of the golf club of the device with the shaft in extended position; and

FIG. 4 is an exploded top plan view showing the elements of the device in position for putting the ball into the golf cup portion of the stand.

Similar numerals refer to similar parts throughout the several views.

The invention comprises a main body portion such as a stand 10 having a recessed portion 12, another recessed portion 14, a centrally open portion 16, and an open side edge 18. There may be a reinforcing strip 20 associated with the open side edge 18. I may provide a rabbed edge 22 around the upper rim of opening 16 as a seat for an ash tray, or ash receiver 24. The ash tray is illustrated as a useful article which may be combined with the ornamental device of the invention. This could be substituted with a clock, a writing pad or any other type of useful article which would normally be used at a desk or table, the only requirement being that when the ash receiver 24, or such other article, is removed from

2

the frame 10, that there will be an open edge 18 and a central opening 16 adapted to be used as a golf cup and to receive a moving golf ball which is struck properly, to be aimed toward said edge 18 and the central opening 16. The term "golf cup" is used in its generic sense to mean an enclosure with an entrance into which a golf ball may be aimed.

Recessed portion 12 is longitudinal in shape, and is adapted to receive the club head 26 of a golf club 28. Golf club 28 has a telescopic shaft 30 and a club handle 32. Recessed portion 14 is circular and is adapted to encompass a golf ball 34.

When the invention is assembled as an ornamental stand, the ash tray 24, or other useful article, will rest on the stand means 10 generally over open portion 16, the golf club 28 will be fitted within longitudinal slot or recess 12, and the golf ball will be resting in its recess 14. The club 28 will have its shaft 30 telescoped to its shorter position. When it is desired to use the invention as a golf playing device, the ash tray 24, or other article is removed. The platform 10 is placed on the floor, or other playing surface, and the ball 34 and club 30 are used in the usual manner to strike the ball 34 so that it will enter open edge 18 and go into open portion 16 as indicated in FIG. 4 of the drawings. When golf club 28 is used as a golf device, shaft 30 is telescoped outwardly to its longer position.

While I have described my invention in its preferred form, there are other forms which it may take without departing from the spirit and scope of the invention, and I, therefore, desire to be protected for all forms coming within the claims hereinbelow.

Wherefore I claim:

1. Golf practice apparatus comprising a putting target including a vertically upstanding peripheral wall having a top surface and defining a circular opening simulating a golf putting cup, said wall having a passage therethrough communicating with said opening so that a golf ball may be putted through said passage into said opening, the top surface of said wall including a first aperture removably supporting a golf ball, and a second elongated aperture in which is removably supported the head of a golf club having a telescopically extensible shaft which may be lengthened for use in putting said ball into said target and shortened and supported on said target to provide an ornamental device.
